CLAIM

I claim the ornamental design for a stove hearth pad, as shown and described.

DESCRIPTION

FIG. 1 is a top plan view of a stove hearth pad showing my new design;

FIG. 2 is a front elevational view of all four embodiments;

FIG. 3 is a rear elevational view of all four embodiments;

FIG. 4 is a right side elevational view of all four embodiments;

FIG. 5 is a left side elevational view of all four embodiments;

FIG. 6 is a top plan view of a stove hearth pad showing second embodiment of my new design;

FIG. 7 is a top plan view of a stove hearth pad showing a third embodiment of my new design; and,

FIG. 8 is a top plan view of a stove hearth pad showing a fourth embodiment of my new design.
